SAFETY WINDOW SEAT

Edward A. Favre, Waltham, Mass.

Application November 15, 1945, Serial No. 628,802

7 Claims. (Cl. 304—27)

1

This invention relates to improvements in supporting means and has particular reference to an improved safety device and method of making the same.

One of the principal objects of the invention is to provide an improved safety device for general utility as supporting means, wherein it is desired to gain access to the exterior of windows or the like, in instances wherein the said windows are located at a considerable distance from the ground and has particular reference to the method of making said device.

Another object is to provide support means which may be quickly secured in operative position and on which a person may be supported in comfort and safety.

Another object is to provide an improved safety device of the above character which is light in weight, durable and constructed so that the parts thereof may be folded in compact relation with each other for ease in handling or storing when not in use.

Another object is to provide an improved safety device which may be attached in position of use without danger of injury to the means with which it comes in contact.

Another object is to provide a safety device which may be quickly erected in position of use and has particular reference to the method of making the same wherein the action of its holding means will be increased by the weight of the individual it is supporting.

Another object is to provide a safety device having means so constructed as to provide means for preventing the soiling of the garment of the user.

Another object is to provide improved means for facilitating the washing of the exterior of windows with ease, comfort and safety.

Another object is to provide a simple, inexpensive and efficacious safety device of the above character and method of making the same.

Other objects and advantages of the invention will become apparent from the following description taken in connection with the accompanying drawings and it will be apparent that many changes may be made in the details of construction, arrangement of parts and methods shown and described without departing from the spirit of the invention as expressed in the accompanying claims. I, therefore, do not wish to be limited to the exact details, arrangements and methods shown and described as the preferred forms only have been shown by way of illustration.

Referring to the drawings:

2

Fig. I is a perspective view of a device embodying the invention showing it in position of use;

Fig. II is a side elevation of a modified form of the invention;

Fig. III is an enlarged fragmentary sectional view taken on line III—III of Fig. I;

Fig. IV is a slightly enlarged view of one of the gripping members showing a step in the process of manufacture;

Fig. V is a view similar to Fig. IV illustrating one of the previous steps in the process of manufacture;

Fig. VI is a view generally similar to Fig. I of a further modification of the invention;

Fig. VII is a side elevational view of a further modification;

Fig. VIII is a view generally similar to Fig. VII of a still further modification;

Fig. IX is a fragmentary enlarged sectional view of a modified attachment of sling to its supporting frame;

Fig. X is a slightly enlarged fragmentary sectional view taken on line X—X of Fig. VII;

Fig. XI is an enlarged fragmentary sectional view of a modified form of attachment of back member to its supporting frame; and

Fig. XII is a fragmentary perspective view shown partially in section of a modified form of the invention.

It has been found in the past that much difficulty and danger has been encountered in washing the exterior of windows, particularly in instances such as in dwelling houses wherein the windows are located at a considerable height from the ground. It has been usual in the past to sit on the sill of the window with no definite means of support. This has not only been very dangerous but exceptionally uncomfortable, causing such work to be very tedious and laborious. It, therefore, is one of the primary objects of my invention to provide simple, portable means which may be quickly and easily attached to the sill of a window and which will provide safe and comfortable means for supporting a person exteriorly of said window and yet permit the free use of both hands in accomplishing the work to be done.

It is apparent that the device may have many other uses than the one specifically described above and all are included in this invention.

Referring more particularly to the drawings wherein similar reference characters designate similar parts throughout the several views, the device embodying the invention comprises a main frame 1 formed preferably of tubular material

such as piping which is bent at 2 to form a frame support for the back rest 3 and to form depending supporting portions 4. The bent portion 2 is flattened and slotted at 5 as shown in Fig. III to receive the angled peripheral lip 6 of the back rest 3. The said back rest is secured to the bent portion 2 by rivets of like means 7 which extend through aligned openings formed in said bent portion and the peripheral lip 6. The lower peripheral lip portion 6 is bent to lie substantially parallel with the plane of the back rest 3 and forms attaching means for receiving one end of a flexible seat or sling 8 formed of canvas, leather or any other suitable material. The said end is connected to the attaching means by rivets or the like 9 which extend through aligned openings in the lower end of the back rest and the parallel lip portion 6. To aid in holding the flexible material in position between said back rest and adjacent parallel lip portion 6 there is provided a section of flat bar material 10 about which the end of the seat or sling is wrapped. The said bar material is held in place by the rivets 9, as shown in Fig. III.

The depending portions 4 are provided with bent lower ends 11 for engaging the means to which the device is attached such as the outer side wall of the house. To prevent scratching or otherwise injuring the said wall the ends are provided with a cushion covering 12 such as rubber tubing, leather, cloth, cork or other suitable means. To aid in supporting the said depending portions 4 in definite spaced relation and to provide attaching means for the opposite end of the flexible seat or sling 8 there is provided a cross support 13 attached by rivets, bolts or other means 28 adjacent the lower bent ends 11 of the depending portions 4. To aid in supporting the device in position of use there is provided a pair of arms 14 pivotally attached at 15 by bolts, rivets or other means to the side frame 2 of the back rest 3. The said arms 14 are formed preferably of tubular stock such as pieces of piping which are flattened at their attaching ends 15 and split adjacent their opposite ends 16 as shown in Figures IV and V. The said split ends 16 are flared outwardly at 17 and are each provided with an opening 18 which communicates with the bottom of the split end portions 16. The said openings provide attaching means for receiving a spacing bar 19. The said bar has hook shaped gripping ends 20 formed thereon for gripping the means to which the device is attached, as for example the sill of a window, as shown in Fig. I. The hook shaped ends 20 are adapted to be placed through the opening 18 in each of the arms 14 and are adapted to be sealed in the split end portions 16 by closing the outwardly flared portions 17, as shown in Fig. IV. The hook shaped gripping ends 20 are covered with rubber tubing, felt, leather or any suitable cushion means 21.

The flexible seat or sling 8 is folded over and attached to the spacing bar 19 by stitchings or any suitable means 22 to form the seat portion 23 and a flexible connecting portion 24 is provided between the said spacing bar 19 and lower cross support 13. The lower end of the seat or sling 8 is attached to the cross support 13 by stitchings 25 or any suitable means.

To cause the seat portion 23 and flexible connecting portion 24 to be urged toward each other when the device is not in use and to prevent the seat portion 23 from being displaced during the use thereof there is provided a resilient member such as an elastic band or other suitable means 26.

In Fig. II there is shown a slight modification wherein the arms 14 are eliminated and the seat portion 29 forms the means for supporting the back rest portion 30 during the use of the device. A spacing bar 31 of a shape similar to the bar 19 is attached to the flexible seat or sling 29 in a similar manner to that described for the bar 19 and is provided with the usual hook shaped ends 32 for gripping the sill or means to which the device is attached. The remaining parts and structure of the device is similar in detail to the device shown and described above in Fig. I. The only difference between this modification and the first described form is the elimination of the side arms 14.

Attention is directed to the fact that the hook shaped gripping portions 20 and 32 as well as the bent ends 11 are shaped to provide a broad contact bearing surface and are covered with suitable means such as rubber, cork, felt, leather or other means which will form friction bearing means to aid in preventing the device from slipping during the use thereof.

In use, the hook shaped ends 20 or 32 are first attached to the sill of the window and the back rest is extended outwardly of the window and allowed to settle in position with the lower connecting portion 24 or 33 overlying the sill and the bent ends 11 or 34 engaging the side wall of the house. The device is then ready for use and is adapted to provide comfortable and safe means on which a person may be supported and permitted use of both hands in accomplishing the work to be done.

Although applicant has shown and described the use of tubular material it is to be understood that any suitable type of material may be used.

In Fig. VI there is illustrated a further modified form of the invention. In this figure the frame 35 is provided with a relatively narrow back member 36. The back 36 is secured to the adjacent portion of the frame throughout its contour edges 37, as shown in Fig. XI, as by welding, soldering or the like.

The side arms 38 are respectively pivotally secured to the frame 35 as by bolts, rivets or the like 39 and are provided with an integral cross or tie portion 40 formed by bending the arms at 41. The cross or tie portion, in this instance, forms the means to which the adjacent end of the seat or sling 42 is attached. The attachment is made by folding the end over the cross or tie portion and stitching the superimposed portions together. If desired, the said superimposed portions may be cemented or adhesively joined with each other by a layer of suitable cement or adhesive 42, as shown in Fig. IX or may be both cemented and stitched if desired, as shown in said figure. The stitchings are illustrated at 43.

The seat or sling extends over a cross bar 44 and is provided with superimposed portions 45 and 46 which are joined with each other as by a line of stitchings or the like 47. The seat or sling 42 then extends downwardly and has its lower end attached to a bar 48 in a manner similar to the end attached to the cross or tie member 40.

The cross bar 44 is attached adjacent the forward ends of the arms 38 by rivets or the like 49 and the said ends are each provided with a hook shaped portion 50 to hook over the window sill or the like 51. The said ends are each covered with cushion means such as rubber, leather or the like.

The bar 48 is secured adjacent the lower ends 53 of the side portions 35 by rivets, bolts or the like 52 and the said ends 53 are covered with suit-

able cushion bearing means such as rubber, leather or the like. The arms 38 and the side portions 35 are joined with each other by link members 54 and 55 pivotally joined with each other at 56 and with the said arms 38 and side portions 35 at 57 and 58 respectively. This arrangement permits the device to be quickly and easily folded for ease of conveyance or storage by moving the link members 54 and 55 relative to each other, as illustrated by the dash lines 59 in Fig. VI. The seat or sling overlying the sill provides means for preventing the users' clothes from becoming soiled by dirt, dust or the like which might collect on the sill.

In Fig. VII there is illustrated a further modification having side portions 60 pivotally attached at 61 to portions 62 having hook shaped ends 63 forwardly thereof and which are pivotally attached at 64 to the back frame 65.

The portions 60 are each provided with rearwardly extending portions 66 having a longitudinal slot 67 therein. The said portions 66 are slidably attached to back frame 65 by headed pins or the like 68 which extend through the slots 67.

The portions 62 are provided with a rear cross or tie member 69 to which one end of the seat or sling 70 is attached and the opposed end thereof is attached to a cross brace 71 secured adjacent the hooked ends 63 by rivets or the like 72. The parts are folded in compact relation with each other by moving the portions 62 in the direction of the arrow 73.

It is to be understood that the hook shaped portions 63 and the lower ends 74 are each covered with cushion bearing means such as rubber, leather or the like as in the previous constructions. The depending side portions of the back frame 65 are joined adjacent the ends 74 by a tie member 75.

The back member 76 in this construction is provided with recesses 77 through which the ends 66 may slide, see Fig. X.

In Fig. VIII there is shown a still further modification embodying a structure generally similar to Fig. VI with the exception that chain sections 78 are employed for joining the portions 38' and 35' instead of the link members 54 and 55. The seat or sling 42' is secured adjacent its opposed ends to the cross bars 40' and 44' respectively.

In Fig. XII, there is shown a still further modification wherein the side supports 79 are pivotally connected at 80 directly to the cross or tie member 81 of the main back frame 82. In this instance, the seat or sling 83 is also connected directly to the cross or tie member 81, as illustrated at 84.

From the foregoing description it will be seen that I have provided simple, efficient and durable means and methods of obtaining all of the objects and advantages of the invention.

Having described my invention I claim:

1. A device of the character described comprising a U-shaped main frame portion having a back portion located at the base of the U and having its opposed ends provided with bearing portions, means for connecting the opposed ends together, a pair of supporting members having hooked portions pivotally connected to the main frame member and having hooked portions adjacent the free ends thereof, means for connecting the supporting portions with each other adjacent said free ends, foldable means connecting said supporting portions with the branches of the U-shaped main frame member at points

spaced at the pivotal connections and a seat of collapsible flexible sheet material having one end supported adjacent the back portion and having the portion overlying the means connecting the free ends of the supporting portions and secured in said relation.

2. In a device of the character described the combination of a main frame member having a back portion adjacent one end thereof, depending side portions and means for joining said depending portions adjacent the free ends thereof, supporting means embodying spaced portions joined by a transversely extending portion adjacent one end thereof and pivotally connected to the frame member adjacent the back portion, said spaced portions each having hooked portions adjacent the free ends thereof, barlike means connecting said free ends, adjustable means joining the spaced portions of said supporting means with the respective depending portions of the main frame member at points spaced from the pivot means and a seat of collapsible flexible sheet material carried by said means joining said depending portions and having a portion overlying the means connecting the free ends of said spaced portions of the supporting means.

3. In a device of the character described a main frame member having an upper transversely extending portion and spaced depending portions, said depending portions having bearing means adjacent the lower ends thereof, means extending transversely of said depending portions adjacent said lower ends for retaining said ends in fixed relation with each other, a pair of arms pivotally connected to said depending portions at points spaced from the upper ends thereof, each of said arms having a hook-like portion adjacent the ends thereof opposed to the pivots, means extending between the forward ends of said arms adjacent the hook-like portions for retaining said arms in spaced relation with each other, a member extending between said depending portions intermediate the upper and lower ends thereof, a seat of collapsible flexible sheet material secured adjacent one end thereof to said last named member and having a portion secured to the means extending between the arms adjacent the hook-like portions and means extending between said arms and the parts of the depending side portions below the pivots for restricting the outward pivotal movement of said arms and said depending portions with respect to each other, said last named means being collapsible for permitting the arms to be folded in adjacent compact relation with the depending portions when the device is not in use.

4. In a device of the character described a U-shaped main frame member having an upper transversely extending portion and spaced depending portions, said depending portions having bearing means adjacent the lower ends thereof, means extending transversely of said depending portions adjacent said lower ends for retaining said ends in fixed spaced relation with each other, a U-shaped support embodying a pair of arms pivotally connected to said depending portions at points spaced from the upper ends thereof, each of said arms having a hook-like portion adjacent the forward ends thereof and having its base extending between the depending portions rearwardly of the pivots, means extending between the forward ends of said arms adjacent the hook-like portions for retaining the forward ends of said arms in spaced relation with each other, a seat of collapsible flexible sheet material secured

adjacent one end thereof to said base and having a portion secured to the means extending between the arms adjacent the hook-like portions and means extending between said arms and the parts of the depending side portions below the pivots for restricting the outward pivotal movement of said arms and said depending portions with respect to each other, said last named means being collapsible for permitting the arms to be folded in adjacent compact relation with the depending portions when the device is not in use.

5. A device of the character described comprising a pair of main support members formed rigid throughout the length thereof and pivotally connected with each other so as to permit folding of one of said members into adjacent compact relation with the other, one of said members having hook-like portions located adjacent the forward end thereof and the other of said members having a bearing portion located adjacent the lower end thereof, means extending between said members intermediate the ends thereof for restricting the outward pivotal movement of said members relative to each other, said last-named means being collapsible for permitting said members to be folded in adjacent compact relation with each other while the various members and means are retained in their initial assembled relation with each other, one of said members having tie means extending transversely intermediate said member and a seat having a forward end portion secured to said main support members adjacent said hook-like portions and having a portion overlying the tie means and arranged to permit said main support members and said seat to be folded into compact relation with each other.

6. A device of the character described comprising a pair of main support members formed rigid throughout the length thereof and pivotally connected with each other so as to permit folding of one of said members into adjacent compact relation with the other, one of said members having hook-like portions located adjacent the forward end thereof and the other of said members having a bearing portion located adjacent the lower end thereof, means extending between said members intermediate the ends thereof for restricting the outward pivotal movement of said members relative to each other, said last-named means comprising two sections pivotally connected to each other adjacent one of their respective ends and having their opposed ends pivotally connected one to each of the respective main support members and being collapsible for permitting said members to be folded in adjacent compact relation with each other, one of said members having tie means extending transversely intermediate said member and a seat having a forward

end portion secured to said main support members adjacent said hook-like portions and having a portion overlying the tie means and arranged to permit said main support members and said seat to be folded into compact relation with each other.

5 7. A device of the character described comprising a pair of main support members formed rigid throughout the length thereof and pivotally connected with each other adjacent one end thereof so as to permit folding of one of said members into adjacent compact relation with the other, one of said members having hook-like portions located adjacent the forward end thereof and the other of said members having a bearing portion located adjacent the lower end thereof, means extending between said members intermediate the ends thereof at a location spaced from the pivot for restricting the outward pivotal movement of said members relative to each other, said last-named means being collapsible for permitting said members to be folded in adjacent compact relation with each other while the various members and means are retained in their initial assembled relation with each other, one of said members having rigid tie means extending transversely intermediate said member and a seat having a forward end portion assembled with said main support members adjacent said hook-like portions and having a portion overlying the tie means and arranged to permit said main support members and seat to be folded into compact relation with each other.
